UNITED STATES PATENT OFFICE.

HEINRICH EGBERTS, OF BREMEN, GERMANY.

HOLDER FOR UMBRELLAS, CANES, &c.

SPECIFICATION forming part of Letters Patent No. 499,974, dated June 20, 1893.

Application filed December 31, 1891. Serial No. 416,681. (No model.) Patented in Austria-Hungary May 13, 1891, No. 58,401 and No. 7,288; in Germany June 12, 1891, No. 60,693; in England December 7, 1891, No. 21,385; in France December 8, 1891, No. 217,924, and in Belgium December 9, 1891, No. 97,507.

To all whom it may concern.

Be it known that I, HEINRICH EGBERTS, of Bremen, Germany, have invented a new and Improved Holder for Umbrellas, Sticks, Pipes, and Similar Articles, (patented in England, No. 21,385, dated December 7, 1891; in France, No. 217,924, dated December 8, 1891; in Austria-Hungary, No. 58,401 and No. 7,288, dated May 13, 1891; in Belgium, No. 97,507, dated December 9, 1891, and in Germany, No. 60,693, dated June 12, 1891,) of which the following is a full, clear, and exact description.

My improvement is embodied in three connected and co-operating parts, to wit, (first) a plate having recesses to receive the umbrella handles, canes, &c.; (second) cruciform rotatable devices, which are pivoted adjacent to said recesses, on the side, and project into the latter as they rotate; and (third) spring pawls or detents that engage the arms of said devices in the manner hereinafter described.

Reference is to be had to the accompanying drawings, forming a part of this specification, in which similar letters of reference indicate corresponding parts in all the figures.

Figure 1 is a side elevation of the holder embodying my invention. Fig. 2 is an inverted plan of the same. Fig. 3 is a front elevation of the bottom trough which may be used in connection with the holder. Fig. 4 is a front elevation of the holder and trough showing a cane and umbrellas held in position therein; and Fig. 5 is a vertical cross section through the bottom trough.

The holder is provided with a plate *b*, which has a series of parallel recesses *b'*, opening inward from the front edge and adapted to receive the various articles, and on the under side of the plate and following its front edge is a depending flange *b*², which is broken away at intervals to provide for the movement of the cruciform holders or cross pieces, as hereinafter described. On the back edge of the plate *b* is a flange *y'*, having perforations therein to receive screws *y*, by which the holder may be secured to a wall.

Pivoted on the under side of the plate *b* and adjacent to the recesses therein are the cruciform holders or cross pieces *a*, the arms of which are adapted to swing into the re-

cesses *b'*, and these cruciform holders are pivoted upon studs *c*, and held in place by split pins *c'*, or their equivalents which pass transversely through the lower ends of the studs *c*. The arms of the cruciform pieces *a* are 55 adapted to swing successively into the recesses *b'* and to lock the umbrellas or other articles between them and the inner walls of the recesses.

The cruciform pieces are held in place and 50 prevented from easy turning by the bent pawls *d*, which are pivoted on the underside of the plate *b* near the back thereof, and which are mounted on pins *f*. The pawls *d* are bent or curved so that their free ends will come 55 behind one of the arms of the cruciform pieces and the body portion of the pawl will extend into the path of another arm, and the pawls will thus prevent the cruciform pieces from turning freely in either direction.

The pins *f* carry springs *e*, the free ends of which engage studs *d'* on the pawls *d* and thus press the pawls into engagement with the cruciform pieces *a'*. The pawls and springs are held in place by pins *f'*, as shown 75 in Figs. 1 and 2. To prevent the floor or carpet from being soiled, the bottom trough *H*, is used which trough is placed directly beneath the holder so as to receive the lower end of the articles held by the holder, and the 80 trough may be of any approved construction and is preferably provided with perforated flanges *H'* at its back upper edge to facilitate its attachment to the wall. To hold an umbrella or other article the lower end of the 85 umbrella is placed in the trough and the upper end pushed into one of the recesses *b'*, thus swinging the one arm of a cruciform piece out of the way and causing another one to swing into place so as to properly secure 90 the umbrella.

It will be understood that the pawls *d* by reason of their bent shape will hold the cruciform pieces in place, but will still permit them to be turned when an umbrella or other article is inserted in the holder, and it will be also understood that these cruciform pieces may be dispensed with and other forms having projecting arms employed, for instance 95 the form of a star.

Having thus fully described my invention, I claim as new and desire to secure by Letters Patent—

1. In an umbrella-holder, the combination with the plate *b*, having recesses *b'*, of the cruciform devices, *a*, pivoted adjacent to one side of said recesses, as shown, so that their arms project into the latter as they revolve, and the spring-actuated detents, *d*, secured to the plate, *b*, in the same plane with the arms of devices, *a*, and arranged with free ends in engagement with the outer ends of the afore-said arms, as shown and described: 25
2. A holder for umbrellas and the like comprising a plate or base, having a recess leading inwardly from one edge thereof, and a pivoted retaining device having radiating arms which project into said recess when the retaining device is rotated, and the walls of the recess within or behind the projecting arms of the retaining device forming in connection with the latter a support for an umbrella or like article when secured in place, and a spring 30
- 15
- 20

retarder acting as a brake upon the retaining device, substantially as described! 25

3. A holder for umbrellas and the like comprising a base plate or body having a recess leading inwardly from one edge thereof, a revolute retaining device whose radiating arms project into said recess as the retainer is rotated and a spring actuated pawl projecting into the path of the arms for contacting therewith and resisting, by its pressure, the movements of said retainer, the latter being revolute in both directions, and its arms being 35 adapted to slip by the pawl irrespective of the direction of rotation, for permitting the ready insertion and removal of the umbrella or other article, substantially as described!

In witness whereof I have hereunto set my hand in presence of two witnesses: 40

HEINRICH EGBERTS.
